Primary Examiner — Cynthia M Chin

(57) **CLAIM**

The ornamental design for a construction set block, as shown and described.

DESCRIPTION

FIG. 1 is a first perspective view of a construction set block showing our new design;

FIG. 2 is a second perspective view of the construction set block showing our new design;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1; and,

FIG. 8 is a bottom plan view of FIG. 1.

The broken lines are for the purpose of illustrating portions of the article that form no part of the claim.
